[57] CLAIM

The ornamental design for a combined head and back support to facilitate washing hair in a bathtub, as shown and described.

DESCRIPTION

FIG. 1 is a front, left side perspective view of a combined head and back support to facilitate washing hair
in a bathtub showing my new design;

FIG. 2 is a rear, right side perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof; and,

FIG. 8 is a left side elevational view thereof.
